GARMENT

Filed April 12, 1928

UNITED STATES PATENT OFFICE

BERTHA SUZANNE DELONG, OF MINNEAPOLIS, MINNESOTA

GARMENT

Application filed April 12, 1928. Serial No. 269,401.

This invention relates to children's and women's garments in the nature of under-wear, dresses etc.

It is an object of this invention to provide a garment adapted to fit the body of a wearer and having a seat opening in the rear thereof, and a flap adapted normally to cover said opening and to be held in place without use of buttons and buttonholes, clasps, snap fasteners etc., and yet being capable of being operated to expose the seat opening in the garment.

Another object of the invention is to provide a garment for women and children which will fit the body of the wearer and is expandable at the rear side of the waist thereof, to accommodate the garment to bending or similar movement by the wearer.

To these ends, the invention consists in the novel parts and novel combinations of parts, hereinafter defined in the claims and described in the following specification, made in connection with the accompanying drawings, wherein like reference characters refer to the same or similar parts throughout the various views and, in which,

Fig. 1 is a view illustrating a child wearing one embodiment of the garment and showing the drop seat of the garment in one position in full lines, and in another position in dotted lines;

Fig. 2 is a rear elevation on an enlarged scale of the garment illustrated in Fig. 1, certain of the parts being illustrated in one position in full lines, and in another position in dotted lines;

Fig. 3 is a vertical section taken on the line 3—3 of Fig. 2, as is indicated by the arrows;

Fig. 4 is a horizontal section taken on the line 4—4 of Fig. 2, as is indicated by the arrows;

Fig. 5 is a perspective view of a portion of the garment illustrated in Figs. 1, 2, 3 and 4, taken from the inside of the garment looking outwardly;

Fig. 6 is a perspective view similar to Fig. 5, of a slightly different embodiment of the invention, and

Fig. 7 is a horizontal sectional view similar

to Fig. 4 of the garment embodied in the structure shown in Fig. 6.

Referring to the drawings, Figs. 1, 2, 3, 4 and 5, a child's or woman's undergarment A is illustrated which is adapted to fit the body of the wearer and which may be supported as by shoulder straps 8 in the usual manner. A seat opening 9 is provided at the rear side of the garment across the back thereof, and from adjacent the waistline of the garment to the crotch portion thereof. A flap 10 projects downwardly from the waistline of the garment into the seat opening some little distance. To cover the opening 9, a rectangular flap or drop seat 11 is provided at the rear of the garment. This flap 11 extends upwardly from adjacent the lower portion of the rear side of the garment to a point just above the waistline and the top edge of the flap 11 has formed thereon an elastic cord holder 12 forming a continuous passage from one edge of the flap to the other edge thereof. The cord holder 12 is preferably formed by either bending over the extreme upper edge of the flap 11 on itself and sewing the bent over portion to the main portion thereof, or else the holder may be formed by sewing an extra strip along the top edge of the flap 11. Preferably a double band of non-electric material is sewed to the waistline of the garment to form a cord holder 13 which extends from one side of the garment across the front thereof, to the other side of the garment. An endless elastic cord 14 fits within the passages in the two cord holders 12 and 13 and through slits 15 provided at each side of the garment rearwardly from the rear ends of the cord holder 13.

When the garment is being worn by a child or woman, the waist portion will be filled out to stretch the elastic cord 14 slightly and slits will be formed at the sides of the garment projecting downwardly from the waistline thereof. The flap 11 will thus normally extend over the seat opening 9 as is indicated in full lines Figs. 1, 2 and 3 with the upper edge of the flap adjacent the waistline of the garment to entirely close the seat opening. When it becomes desirable to expose the seat opening, the flap 11 may be lowered to the po-

sition illustrated in dotted lines Figs. 1 and 2, and the elastic cord 14 will have sufficient elasticity to permit the flap to be swung downwardly about a portion of the rear side of the garment below the waistline as an axis to expose the entire seat opening 9 of the garment. When released, the elastic cord 14 will again act to return the flap 11 to its normal upwardly swung position. The cord holders 12 and 13 will gather slightly at the waistline 5 of the garment to permit expansion of the waistline as the wearer of the garment bends over or otherwise moves about. Also as the wearer bends downwardly, the flap 11 forming the drop seat will be carried downwardly 10 slightly from the waistline of the garment to prevent binding of the garment around the crotch or legs of the wearer. It will thus be seen that a very comfortable garment is provided having a drop seat which will hold its 15 position under normal conditions to completely close the seat opening in the garment without the use of buttons, hooks or other fasteners. The garment is found particularly useful for small children incapable of operating buttons or other fastening means.

In Figs. 6 and 7, a slightly modified form 20 of garment B is shown. In the garment B, a flap 16 forming a drop seat is provided which is similar in all respects to the flap 11 with the exception that a double elastic cord holder 17 is provided at the upper edge of the flap, rather than a single cord holder 12. Also instead of providing a single cord holder 13 at 25 the sides and front of the garment, the garment B is provided with a single strip 18 which extends across the sides and front of the garment and is stitched at 19 along its two edges to the front of the garment and is stitched by stitching 20 at its center to the two sides of the garment. The central stitching 20 at the sides of the garment leaves the edges of the strip 18 free and a plurality of eyes 21 are provided in double rows in the strip 18 at 30 the two sides of the garment. An elastic cord 22, formed as a double loop, projects through the double openings in the cord holder 17 and through the double rows of eyes 21 and through openings 23 equipped with eyes 35 in the sides of the garment rearwardly from the rear ends of the strip 18. The cord 22 will thus extend from one side of the garment rearwardly across the back of the garment to the other side of the garment. Inasmuch as the strip 18 is stitched to the garment B in the sides thereof, only at its central portion 40, it will be seen that the cord can be readily extended through the various eyes 21 without difficulty. When the double elastic cord 22 is used, the upper edge of the flap 16 will be given slightly more rigidity than is the case where the single cord 14 is used. Thus in the garment B, there will be no tendency for the upper edge of the flap to turn or twist. The flap 16, forming the drop seat of the garment

B, will act like the flap 11 in all respects to close the seat opening in the rear of the garment, or to allow the drop seat to be lowered to expose the seat opening. Also in the garment B, the sides of the waist portion of the 70 garment, as well as the back of the garment, may be expanded to accommodate the garment to movement by the wearer thereof.

In both the garment A and in the garment B, a holder 13 or a cloth band 18 is provided which extends completely around the front of the garments so that the pull at the waistline of the garments will be exerted against a cloth band at the waist of the garments, rather than against the main material of the garments themselves. The waist portions of the garments will therefore not be unduly expanded and the shape of the garments will be maintained.

The invention has been amply demonstrated in actual practice and has been found to be very successful for the purposes intended. The construction is cheap and simple.

It will, of course, be understood that various changes may be made in the form, details, arrangement and proportions of the various parts without departing from the scope of the present invention.

What is claimed is:

1. A garment adapted to fit the body of a 95 wearer, having a seat opening extending downwardly from the back of the waistline thereof, a substantially rectangular flap secured to the lower rear portion of the garment and adapted to cover said opening 100 when upwardly extended, a flexible strip secured to the forward portion of the waistline forwardly of the flap, and an elastic cord mounted in the upper edge of said flap, the forward portions of said cord projecting 105 through portions of the rear ends of said strip and being permanently mounted in said strip, whereby said elastic cord will normally hold said flap in upwardly raised position against the rear portion of the waistline of the garment to close said opening, but will permit said flap to be bodily dropped to expose the said opening without detachment of said cord from said strip, portions of said elastic cord normally projecting through the rear 110 ends of said strip being partially withdrawable to gather the rear portions of said strip and thereby afford long active and stretchable lengths of the elastic cord between the rear ends of the strip and the side edges of 115 said flap.

2. A garment adapted to fit the body of a wearer, having a seat opening extending downwardly and below the rear waistline of the garment, a rectangular flap formed 125 at the rear lower side of the garment and adapted to be projected upwardly to fit over said opening, a strip of material secured to the forward waistline of the garment, a cord holder formed at the upper edge of said flap 130

- and an endless elastic cord formed in a loop, both runs of which project through said cord holder and through the portions of said strip adjacent the sides of said flap, whereby the 5 waistline of said garment will be expansible and said cord will normally hold said flap in upwardly raised position to close said seat opening, but will permit the flap to be bodily dropped to expose said seat opening, the two 10 runs of the endless cord tending to prevent the upper edge of said flap from twisting.
3. A garment adapted to embrace the body of a wearer, having a seat opening extending downwardly and below the rear waistline of 15 the garment, a flap having top and side edges and secured at the rear lower side of the garment and adapted to be projected upwardly to fit over said opening, a cord holder formed at the upper edge of said flap and two elastic 20 cords projecting through said cord holder and held in spaced relation thereby, said elastic cords projecting laterally from the two sides of said flap, and being secured at their forward portions to the waistline of the 25 garment forwardly from the sides of said seat opening, whereby the waistline of said garment will be expansible and said elastic cords will normally hold said flap in upwardly raised position to close said seat open- 30 ing but will permit said flap to be bodily dropped to expose said seat opening, the two elastic cords acting to prevent the upper edge of said flap from twisting.
4. A garment adapted to embrace the 35 body of the wearer, having a seat opening extending downwardly from the back of the waistline thereof, a flap having top and side edges and secured to the lower rear portion of the garment, and elastics carried by the 40 upper edge of said flap and running forwardly from the side edges thereof, the forward portions of said elastics passing through portions of the waistline of the garment adjacent the edges of said seat opening and be- 45 ing secured in fixed relation to the waistline of the garment in forwardly spaced relation from the edges of said seat opening, whereby said elastics will normally act to hold said flap in raised position over said seat open- 50 ing but will be withdrawable for a considerable portion of their lengths from said portions of the waistline to permit gathering of the waistline and afford long, active lengths of the elastics between said portions of the 55 waistline and side edges of said flap to permit said flap to be bodily swung downwardly to widely expose said seat opening without detachment of said elastics from the waistline.
5. A garment adapted to embrace the body 60 of a wearer, having a seat opening extending downwardly from the back of the waistline thereof, a flap having top and side edges secured to the lower rear portion of the garment and adapted to cover said opening when upwardly extended, a flexible strip secured 65
- to the inner side of the waistline forwardly of the edges of the seat opening and elastics mounted at the top of said flap and extending laterally of the edges of said flap, the forward portions of said elastics projecting inwardly 70 through the waistline of the garment adjacent the edges of the seat opening and being permanently mounted in said strip, whereby said elastics will normally hold said flap in upwardly raised position against 75 the rear portion of the waistline of the garment to close said opening, but will permit said flap to be bodily dropped to expose the said opening without detachment of said elastics from said strip, forward portions of said elastics projecting inwardly through the waistline of the garment being partially withdrawable to gather portions of the waistline of the garment between the points of attachment of the elastics to said 80 strip and the portions through which said elastics extend and thereby afford long and stretchable lengths of the elastics between the points of attachment of the elastics to the strip and the edges of said flap.
- In testimony whereof I affix my signature.
